UNITED STATES PATENT OFFICE.

JAMES B. ALLFREE, OF CUMBERLAND, MARYLAND, ASSIGNOR OF ONE-HALF
TO ROBERT SHRIVER AND HARRISON SWARTZWELDER, BOTH OF SAME
PLACE.

JOURNAL-BOX.

SPECIFICATION forming part of Letters Patent No. 351,015, dated October 19, 1886.

Application filed June 23, 1886. Serial No. 205,996. (No model.)

To all whom it may concern:

Be it known that I, JAMES B. ALLFREE, a citizen of the United States, residing at Cumberland, in the county of Alleghany and State of Maryland, have invented new and useful Improvements in Eccentrics and Journal-Boxes, of which the following is a specification.

This invention relates to certain new and useful improvements in eccentric journals and journal-boxes; and it consists, substantially, in such features of construction and combinations of parts as will hereinafter be distinctly described, and pointed out in the claims.

15 The objects of the invention are, first, to provide a journal box or bearing of such construction as that a self and continuous supply of oil or lubricant will be had for the eccentric journal during its rotation or movement 20 in the box, thus promoting the longevity of wear of the parts, and obviating the necessity of frequent replenishing of lubricant.

Second, the invention has for its object to provide simple and effective means by which 25 the eccentric journal is made variable with respect to the driving-shaft for increasing or diminishing the stroke of the rod or other device designed to be operated, and by which the said eccentric journal may be adjusted 30 horizontally to set or bring it to the proper position.

Finally, the invention has for its object to simplify the construction of parts, and to economize in cost over many former inventions of an analogous character, all as will appear from the description hereinafter following.

Referring to the accompanying sheet of drawings, Figure 1 represents an end view of an 40 eccentric journal and journal-box embodying the principles of my invention. Fig. 2 represents a vertical sectional view of the journal-box on the line $\alpha\alpha$ of Fig. 1, by which the interior construction of the same is more clearly 45 understood; and Fig. 3 represents a longitudinal sectional view to indicate more clearly the manner of adjustment of the eccentric journal horizontally, and of varying its eccentricity with respect to the driving-shaft.

50 In carrying my invention into effect I pro-

vide a journal-box, A, preferably divided or split at the top, as at a , and held together by an adjusting-screw, b , by which a regulation of the ease of movement of the eccentric journal is had and the wear of the parts compensated or taken up. This box is provided with 55 an annular flange, c , which surrounds the inner end of the opening in the box, as shown, and is for the purpose of preventing the journal-box from slipping away from the eccentric 60 journal, and also of preventing the escape of lubricant from that end of the box. At the opposite end of the box, on the interior thereof, an annular groove or chamber, d , is formed, that is designed to catch or receive the oil 65 thrown off from the outer end of the eccentric journal centrifugally during the rotation thereof through its connection with the driving-shaft, while in the bottom of said box a longitudinal groove or chamber, e , is formed, 70 the same being designed as the reservoir for the oil, and as a conduit to convey the oil back to the body of the eccentric journal B. The eccentric journal is constructed of such length as to have its outer end or edge extend past the 75 inner wall, and about opposite the middle of the annular groove d .

By the construction thus far explained it will be seen that by placing a suitable quantity of oil or other proper lubricant in the longitudinal 80 groove e the rotation of the eccentric journal within the box will cause it to gradually spread around and be carried out centrifugally at the end, where it is caught or received by the annular groove d , from whence it gravitates or flows 85 back into the longitudinal groove or reservoir e , and thence back to the eccentric journal, thus obtaining a self and continuous oiling of the parts. The eccentric journal B is formed or provided with a stem, f , by which it is adjustably connected to the driving-shaft C by means of a set-screw, g . When only the degree of thrust is desired as is permitted by the difference between the geometric centers of the eccentric proper and its stem f , I provide the 95 end of the drive-shaft C with a central bore—that is, with a bore whose center is coincident with the center of the eccentric—and thus will this particular degree of thrust or eccentricity be had; but when a variable degree of eccen- 100

tricity is required I form the bore in the driving shaft to one side of its geometric center, and at a distance therefrom about equivalent to the eccentricity of the eccentric pin, and obtain the stroke desired by rotating the eccentric until the requisite stroke is reached, and then securing it by the set screw *g* at such point horizontally as to permit proper action, and thus will it be seen that a most thorough 10 adjustment or regulation is effected.

It is obvious that instead of forming the eccentric journal and its stem integral or in one piece, the same may be formed separately and then united by any proper method.

15 On one side of the box *A* an extension, *h*, is formed, by which suitable attachment there-of may be made by a screw and nut to the rod or other device to be operated.

20 The invention was devised more particularly for use in roller flour-mills, and for the purpose of operating the shaking or vibrating shoes of the hoppers through which the coarse cereal or grain is fed to the rolls, it being frequently desirable to vary or alter the 25 degree of movement of such shoes to regulate the delivery of the material. It is evident, however, that the invention is applicable to other purposes—such, for instance, as a connection for pitman rods.

30 From the foregoing description it is thought the operation of my invention will be thoroughly understood, and I would state that while I have herein shown and described certain constructions of parts the same can be 35 very materially changed without departing from the spirit of the invention.

Having thus described my invention, what I claim as new, and desire to secure by Letters Patent, is—

40 1. The combination, with an eccentric jour-

nal and means for operating the same, of a split journal-box having an annular interior chamber at one end and a longitudinal oil-groove in its bottom, substantially as described.

2. The combination, with a journal - box having an annular interior groove at one end and a groove in its bottom, of an eccentric journal arranged so that its outer edge or end is extended past the inner wall and about opposite the middle of said annular groove, and means for adjusting the same, substantially as described. 45

3. The combination, with a journal - box having an annular flange, *c*, at one end, and an annular interior groove at the other, and provided with a groove in its bottom, of an eccentric journal and means for adjusting the same horizontally and to variable degrees of eccentricity, substantially as described. 55

4. The combination of the journal-box having an annular interior groove at one end and a longitudinal groove in its bottom, the drive-shaft bored to one side of its geometric center, and an eccentric journal fitting in such bore, 60 having means for adjustment, substantially as shown and described. 65

5. The combination, with the split journal-box, constructed as described, and having screw *b*, and formed with extension *h*, of the eccentric journal or cam *B*, having stem *f*, the drive-shaft, and the set screw *g*, all as shown and set forth. 70

In testimony whereof I have hereunto set my hand in the presence of two subscribing 75 witnesses.

JAMES B. ALLFREE.
